UNITED STATES PATENT OFFICE.

LOUIS A. SCHMIDT, OF BROOKLYN, NEW YORK, ASSIGNOR TO R. HOE & CO., INC., OF NEW YORK, N. Y., A CORPORATION OF NEW YORK.

ASSOCIATING MECHANISM.

Application filed April 12, 1927. Serial No. 183,151.

This invention relates to certain improvements in associating mechanism for printing machines.

In prior United States Letters Patent No. 572,225 dated December 1, 1896, and No. 1,540,231, dated June 2, 1925 both to E. P. Sheldon, there is disclosed associating mechanism for associating a high speed web and a low speed web or sheet from different sources, certain cutting and collecting cylinders being employed for associating a sheet with the web and cutting a sheet or sheets from the web for association. In the mechanisms shown in these patents, five main cylinders are employed for effecting the cutting, association or collection of the products which the mechanisms are capacitated to produce.

It is the especial object of the present invention to produce a mechanism for associating a high speed web and a low speed sheet or associating two high speed webs in which the desired products can be obtained with a less number of cylinders than used in the constructions referred to.

With this and other objects not specifically referred to in view, the invention consists in certain novel parts, arrangements and combinations which will be fully described in connection with the accompanying drawings and the novel features pointed out in the claims hereunto appended.

In these drawings,—

Figure 1 is a diagrammatic side elevation of so much of the folder end of a printing machine as is necessary for an understanding of the invention;

Figure 2 is a diagrammatic side view showing the arrangement of the parts and the web leads for associating a high speed web and a low speed sheet, and

Figure 3 is a diagrammatic side view showing the arrangement of the parts and the web leads when associating two high speed webs.

Referring now to these drawings and first to Figures 1 and 2, there is shown a construction in which a web is forwarded at high speed and a second web is forwarded at a lower speed. Sheets are cut from this low speed web and associated with a high speed web, this also then being severed, and, in the particular construction illustrated, a low

speed sheet will be associated between two sheets from the full speed web. 55

The low speed web, which in the present instance is a web running at half speed, marked L, is directed from printing mechanism, not shown, over a guide roll 1 and under a tension roll 2 and a guide roll 3 to a pair of cooperating cutting cylinders 4, 5. In the particular construction shown, the cylinder 4 is twice the diameter of the cylinder 5 and is driven at half speed. This cylinder is supported on a shaft 6 and is provided with a pair of oppositely disposed cutting woods 7, 8, with which cooperates a cutting knife 9 on the cylinder 5. This latter cylinder is supported on a shaft 10, the shafts 6 and 10 being suitably mounted in the framing of the machine, indicated at 11. The cylinder 4 is also provided with sheet taking devices, shown in the form of pins 12, 13, which act to take the low speed sheets. 65

The high speed web is marked H and is led from the printing mechanism, not shown, over a tension roll 14 and between a pair of forwarding rolls 15, 16, the latter of which is driven, these rolls being suitably mounted in the side frames 11, and from these rolls 15, 16 the full speed web is forwarded to a second pair of cutting and collecting cylinders 17, 18, suitably mounted on shafts 19, 20 supported in the side frames of the machine. 70

The cylinder 18 is provided with a cutting wood 21 and the cylinder 17 is provided with a cutting knife 22. Each of the cylinders is provided with sets of sheet taking devices, shown as pins, the cylinder 17 having pins 23 and the cylinder 18 having pins 24. 80

These cylinders 17, 18 are, it will be observed, half the diameter of the cylinder 4. In the arrangement shown in Figures 1 and 2, a half speed sheet L' cut from the web L by the cylinders 4, 5, is to be associated between two full speed sheets from the web H, and the half speed sheet L' is forwarded so as to be taken by the pins 23 on the cylinder 17 and brought up to full speed. In the particular construction for effecting this, the cylinder 4 is formed with cut away or depressed portions 25, in advance of which are feeding segments 26 which cooperate with a roll 27 to feed the sheets forward after they are released by the pins 12, 13 and, preferably, a guide 28 is provided for 95

guiding the half speed sheets as they pass to the cutting cylinder 17, this guide cooperating with a roll 29, between which and the cylinder 17 the sheets are fed.

5 Cooperating with the cylinder 18 is a pressure roll 30, between which and the cylinder 18 the associated product is fed to the tapes 31 of a former 32. It will be observed that the cylinders are arranged so that the 10 product is always under the control of the pins 23, 24 of the cylinders 17, 18 until it is passed between the bite of the cylinder 18 and the roll 30, so that there is no tendency of the associated half speed sheet to slip 15 back into the line of cut.

If desired, two full speed webs may be forwarded to the cylinders 17, 18 and collected so as to produce a sixteen page product, and this arrangement is illustrated in 20 Figure 3. When operating in this matter, the cylinders 4, 5 are idle and the two webs L'' and H are both run at high speed. The path of the web L'' is indicated in Figure 1, where it is shown as passing over the tension roll 2 under the guide roll 1 over a tension roll 33 to and between feeding rolls 15, 16, from which the two associated webs go to the cutting and collecting cylinders 17, 18. The parts of the machine may be 25 driven in any suitable way, and gearing for doing this has been shown, but need not be described for an understanding of the invention.

While the invention has been shown in 30 its preferred form and arrangement, it will be understood that certain variations and changes may be made in the specific con-

structions shown and described without departing from the invention as claimed in the appended claims.

What I claim is:

1. The combination of means for forwarding a high speed web, means for forwarding a web at a lower speed, a pair of cooperating cutting cylinders for severing a sheet from the low speed web, a second pair of cutting and associating cylinders to which the high speed web and low speed sheet are forwarded for cutting a sheet from the high speed web, sheet holding means carried by the outer of the last pair of cylinders for positively holding the sheet and web during the last cutting operation, and a folding delivery to which the associated sheets are delivered directly by the sheet holding means. 40 45 50 55

2. The combination of means for forwarding a high speed web, means for forwarding a web at a lower speed, a pair of cooperating cutting cylinders for severing a sheet from the low speed web, a second pair of cutting and collecting cylinders to which the high speed web and low speed sheet are forwarded for cutting a sheet from the high speed web, pins carried by the last pair of cylinders for positively holding the sheet and web during the cutting operation, a pressure roll 60 65 70 75 cooperating with the outer of the last pair of cylinders between which and the cylinder the web is forwarded by the pins, and a folding delivery to which the associated sheets are delivered.

In testimony whereof, I have hereunto set my hand.

LOUIS A. SCHMIDT,
